UNITED STATES PATENT OFFICE.

HERSCHEL M. CONNOR AND DON D. MILES, OF SAN FRANCISCO, CALIFORNIA, ASSIGNEES, BY DIRECT AND MESNE ASSIGNMENTS, OF TWO-FIFTHS TO ALBERT H. HERBERT, ONE-FIFTH TO PANSY I. CONNOR, ONE-FIFTH TO MYRTLE C. MILES, AND ONE-FIFTH TO R. J. GRAF, ALL OF SAN FRANCISCO, CALIFORNIA.

FILM PRINTING AND PROJECTING APPARATUS.

1,249,335.

Specification of Letters Patent. Patented Dec. 11, 1917.

Application filed May 20, 1916, Serial No. 98,884. Renewed October 4, 1917. Serial No. 194,807.

To all whom it may concern:

Be it known that we, HERSCHEL M. Connor and Don D. Miles, both citizens of the United States, both residing at San Francisco, in the county of San Francisco and State of California, have invented certain new and useful Improvements in Film Printing and Projecting Apparatus; and we do hereby declare the following to be a full, clear, and exact description of the invention, such as will enable others skilled in the art to which it appertains to make and use the same.

This invention relates to a film printing and projecting apparatus adapted for amateur and professional use, and has for one of its objects to provide a machine of this character which will be comparatively simple in construction, certain in action, and more efficient in use than those heretofore proposed.

With these and other objects in view the invention consists in the novel details of construction and combination of parts, more fully hereinafter disclosed and particularly pointed out in the claims.

Referring to the accompanying drawings forming a part of this specification in which like numerals designate like parts in all the views—

Figure 1 is a diagrammatic side elevational view of a projecting and printing machine made in accordance with this invention;

Fig. 2 is an enlarged side elevational view of a portion of the parts shown in Fig. 1 illustrating the interior construction of the machine when used for projecting purposes;

Fig. 3 is an enlarged side elevational view of a portion of the parts shown in Fig. 2 with certain additional parts added illustrating the use of the machine for printing purposes; and, Fig. 4 is a longitudinal sectional view particularly illustrating the film reversing mechanism.

1 indicates any suitable support, in this instance shown as a tripod head to which is attached the supporting bracket or member 2, provided with the upwardly extending member 3, and with the downwardly extending members 4 and 5. To the upwardly extending member 3 is pivoted as at 6 the film carrying reel 7, and to the down-

wardly extending member 5 is pivoted as at 8 the film carrying reel 9. The part 3 preferably makes substantially a right angle with the part 2 in order to accommodate the casing 10 which is preferably made rectangular as shown, and said casing is provided with the crank 11 and power shaft 12, to which is rigidly attached the pulley 13, around which the belt 14 passes, and on the pivot 8 is also secured the pulley 15 which likewise accommodates said belt 14. The film is represented at 16, it passes over the guides 17 and 18 into the reel 7, and passes out of said reel over the guide 19 through the casing 10, and over the guide 20 into the reel 9, all as will be clear from the drawings.

21 represents a projecting lens attached to the casing 10 and 22 represents any suitable source of light which is likewise conveniently attached to the casing 10 by means of the connection 23. 24 represents a film meter.

Referring now more especially to Fig. 2, the film 16 conveniently passes through the opening 25 with which the casing 10 is provided, and around the feed sprocket 26 mounted on the shaft 27, turned from the crank 11 by suitable gear connections not shown. After leaving said sprocket 26 the said developed film passes over the guides 28 and 29 to form the loop 30 down past the aperture tube 31 where it is engaged by the feeding pin 32, and is formed into the loop 33, whence it passes over the guide 34 into engagement with the feeding sprocket 35, and out of the opening 36, with which the casing 10 is also provided, and from said opening 36 said developed film 16 passes into the winding reel 9 all as will be clear from Figs. 1 and 2.

The front of the casing 10 is provided with the projecting lens diagrammatically indicated at 21 and at its back, said casing is provided with an enlarged opening 38 adapted to receive the light tight connection 23 between said casing 10 and the lamp house 22, which may be of any suitable construction, and provided with any suitable source of light 39, but preferably in the form of an incandescent lamp, especially made for projecting purposes. 40 indicates any suitable condenser which may be remov-

ably secured to the interior of the casting 10 or otherwise associated with the lamp house 22.

The optical axis of the condenser 40 coincides with the optical axis of the projecting lens 21 and of the aperture tube 31. The feeding sprockets 26 and 35 being suitably rotated by connections not shown, with the crank 11, and the film feeding pins 32 being reciprocated up and down by connections also not shown, from said crank 11, it is evident that the film 16 will be pulled out of the reel 7 and carried past the aperture tube 31, and also rolled up on the reel 9, whereupon light coming from the lamp 39 through the condenser 40 will project the developed pictures on said film 16 through the lens 21 onto any screen or other reflecting object which may be provided.

It often happens that it is convenient or desirable to print pictures from a developed film carrying negatives on an undeveloped film, and this machine may be used for this purpose when the parts are arranged as are indicated in Fig. 3. That is to say, in such cases the film 16 above described is fed through the machine in the same manner as has been already disclosed and simultaneously with the feeding of said film 16 through the machine, there is fed through the machine the undeveloped film 50 in close contact with said film 16. In other words, as is fully illustrated and disclosed in our copending application Serial No. 98883 filed May 20, 1916, and entitled Moving picture machines, we have described an apparatus comprising a pair of film reels or holders here lettered 51 and 52, the reel 51 being adapted to feed out an undeveloped film and the reel 52 being adapted to take up the undeveloped film and we have further disclosed how said undeveloped film may be passed around a sprocket such as 26, past an aperture tube such as 31, and around a sprocket such as 35, and be rolled up on a take up reel such as 52. In the present case the mechanism is the same or substantially the same, and as is indicated in Figs. 3 and 4, this said undeveloped film 50 is in close contact with the developed film 16 illustrated in dotted lines in said Figs. 3 and 4 and in full lines in Fig. 2. That is to say, power being applied to the shaft 200 by any suitable means as for example that shown in our said copending application, the pulley 201 is rotated, which in turn rotates the spring belt 202 and this said belt rotates the pulley 203 constituting a portion of any suitable reversing clutch 65, such for example as that illustrated in our said copending application 98883. This said clutch is provided with the tubular members 205 and 206 which are rotated in predetermined directions according to the direction in which the shaft 200 is rotated, and

said member 205 is provided with the pins 207 adapted to fit in corresponding holes 208 with which the tube or hollow shaft 55 is provided. The take up reel 52 is mounted on said tube 55 while the pay out reel 51 is mounted on the tube or hollow shaft 560 provided with the pins 211 adapted to engage the said member 206 under the control of the clutch. In other words, as is fully disclosed in our said copending application above, the reversing clutch 65 through the means indicated enables the operator to control at will the rotations of the tubes 55 and 560, and thereby the reels 52 and 51, and the two films 16 and 50 being thus fed continuously through the machine together, the developed negatives on the film 16 come opposite the aperture tube 31.

In printing from the film 16 onto the film 50, the lens 21 is removed, and light from any suitable source, not shown, is projected through the opening thus produced, through the shutter 53 and aperture tube 31, whereupon latent images are formed upon the film 50 and said exposed film being wound up on the reel 52, it may be developed in any usual or desired manner.

In the printing of pictures in the manner just disclosed it is an important feature of this invention that we are enabled to use the open ended tube 55, in order to ascertain whether the light is proper and therefore whether or not the developed positives will be correct as to sharpness of definition. In the use of this tube 55 for printing we propose to place therein, at any desired position, a ruby glass 56, so that the images on the negative carried by the film 16 may be viewed through the back of the undeveloped film 50, so that the operator may ascertain from the appearance of these images whether or not the light is right for producing sharply defined positives from said negatives. This ruby glass may be placed in any convenient position in the tube 55, and performs two important functions. In the first place it prevents actinic rays from striking the back of the undeveloped film 50, and thus fogging the film, and in the second place, it provides a uniform color to the images from the film 16, so that the operator has something with which he may compare the observed images and thus make up his mind whether or not they have the right appearance to produce the right results.

In using the tube 55 for the purpose just disclosed, it is convenient to remove the smaller cap 60, with which the larger cap 61, fitting the rear of the casing 10 is provided, so that a clear view of the back of the undeveloped film 50 may be had.

66 represents the sliding rod for removing the closure 67 from in front of the aperture tube 31 also disclosed in our said application above and 68 represents the hinge of the

plate 69 which normally closes the rear end of the said aperture tube 31.

When projecting pictures through this machine it is necessary to swing the said plate 69 from its full line position shown in Fig. 3 upwardly or out of the way as is indicated in Fig. 2, for by this means the aperture through the tube 31 is greatly enlarged for projecting purposes. On the other hand, when printing, as indicated in Fig. 3, a smaller aperture is desired and then the cover plate 67 is pulled or pushed out of the way by means of the rod 66 whereupon a smaller aperture through the plate 69 is had and of the proper size for printing pictures, all as will be further understood from our said co-pending application above.

70 represents an intermittently operating film feeding lever which is provided with an enlarged portion to accommodate a slot in which reciprocates a roller pin carried by a cam, as illustrated; and the cam being rotated by any suitable mechanism, not shown, said lever together with its reduced free end 25 or driving pin 32 is moved up and down on its pivot shown at the left on Fig. 2, whereupon said pin projecting through the usual perforations carried by the film 60, moves said film downwardly as seen in Fig. 2. On the other hand, after said cam and pivot pin have moved in a clockwise direction from the position shown in Fig. 2 through an angle of 180 degrees; a continued motion of said cam and roller pivot will move said lever 70 in the direction of its length or toward the left as seen in Fig. 2, whereupon the driving pin 32 will be withdrawn from the perforations in the film, and again brought to the position shown in Fig. 2, all as is more fully disclosed in our copending application, Sr. No. 98883 filed May 20, 1916, and entitled Intermittent feeding mechanisms. An important feature of this invention resides in the fact that the outer casing

45 10 is chosen of such dimensions that it can accommodate a condensing apparatus 40 which may be secured in the aperture 38, as well as the take up and pay out reels 51 and 52. In other words, the condensing apparatus is readily removable to convert the instrument into a printing device, or the reels are readily removable to convert the instrument into a camera, all as will be clear from Figs. 2 and 4.

55 75 represents ways carried by the inside of the casing 10, fitting in slots 76, carried by the framework 77 of the machine proper, and the moving parts of this machine, as well as the film holding reels 51 and 52 may 60 be readily slid in and slid out of said casing 10, on said ways and grooves. It thus results that it is a comparatively easy matter to remove the mechanism from the casing for the purpose of repairs, for cleaning, or for adjustment, or for any other purpose desired.

The enlarged cap 61 fits and closes the opening 38 when the connection 23 to the lamp house 22 is not employed, as will be clear from Fig. 3.

The operation of this machine will be 70 readily understood from the foregoing, but may be briefly summarized as follows: When it is desired to use the machine as a projector, the parts being in the position shown in Fig. 1, the turning of the crank 11 will 75 unwind the film from the reel 7, pull it down through the opening 25, on the casing 10, cause the said film to pass the aperture tube 31, and out of the opening 36 on said casing, and to be wound up on the reel 9 by means of 80 the belt 14.

Later, when all of the film has been unwound from the reel 7 and it is desired to rewind the same on said reel, the said film 16 may be led up along the dotted line position, shown in Fig. 1, threaded into said reel 7, whereupon the belt 14 may be removed from its full line position shown in Fig. 1, and placed in its dotted line position shown in said figure, whereupon a 90 proper turning of the crank 11 will now unwind the film from the reel 9 and wind it up again on the reel 7, ready for another projection.

When employing this machine as a projecting apparatus, it is necessary to remove from the casing 10 the film reels 51 and 52, as well as the clutch mechanism, 65, so that the machine may accommodate the condenser 40, and it is further necessary to connect 95 the lamp house 22 by a light tight connection, such as 23 with the said casing 10, and it is further necessary to move the aperture closing gate 69 out of the way of the aperture tube 31, as is indicated in Fig. 2. The 100 lens 21 remains in position as shown in the drawings.

On the other hand, when it is desired to employ this machine as a printing device, the reels 51 and 52, as well as the clutch reversing mechanism 65 and its associated parts, are placed in position inside the casing 10, as illustrated in Fig. 3, whereupon the mechanism is so arranged as is disclosed in our said copending application, Serial 110 No. 98883, above mentioned, that the undeveloped film 50 is readily fed out of one reel 51 and readily taken up on the other reel 52 or vice versa. In the meantime a developed film, such as 16, carrying negative 115 pictures of the object to be printed, is fed down simultaneously and in close contact with the undeveloped film 50 and the lens 21, being removed, and the aperture closing plate 69 being closed down in the position 120 shown in Fig. 3, while the sliding plate 67 is removed to produce a smaller aperture, then light from any suitable source not shown, may be allowed to enter through the aperture tube 31, and to strike the developed 125 130

film 16, and produce latent images on the undeveloped film 50. In the meantime the operator by removing the smaller cap 60 with which the larger cap 61 is provided 5 may view the back of the undeveloped film through the tube 55 and ruby glass 56 and thus judge from the appearance of the images appearing on said film 50 whether or not the light is just right for producing the 10 best effects.

It should be mentioned that 53 represents a suitable shutter driven by the gears 81, 82 and carried by the sleeve 83.

It is an important feature of this invention 15 that by the mechanism disclosed, the operator is enabled to print his pictures in full daylight. That is to say, the undeveloped film 50 is kept at all times in a light tight box, while the developed film 16 being 20 already developed can be freely exposed to the light. Not only is the undeveloped film 50 exposed in a light tight box, but it is wound up on a reel such as 52 where it may be preserved in position free from all light 25 and may be carried to any convenient place at any convenient time after exposure and there developed.

The entire mechanism as will be seen from the drawings is exceedingly compact and 30 may be readily carried about by amateurs or professionals much after the manner that kodaks are at present transported. Further the mechanism as above disclosed may be readily slipped in and slipped out of the 35 casing on the ways 75 for the purpose of cleaning or repair, and also in order to facilitate the threading of the films through the mechanism.

The belt 14 is preferably made of a yielding or stretchable material such as rubber or a helically coiled steel spring, so that as the diameter of the coiled film increases said belt will slip while still maintaining the necessary friction to drive said reel.

45 It is obvious that those skilled in the art may vary the details of construction, as well as the arrangement of parts, without departing from the spirit of the invention, and therefore we do not wish to be limited 50 to the above disclosure except as may be required by the claims.

What we claim is:

1. In a film printing and projecting apparatus the combination of a film feeding 55 means comprising rotating sprockets and a reciprocating lever for feeding a developed and an undeveloped film simultaneously through the machine; a pay out reel and a take up reel for holding the undeveloped 60 film; a pay out reel and a take up reel for holding the developed film; and means for operating both of said take up reels from the same shaft, substantially as described.

2. In a film printing and projecting ap- 65 paratus the combination of a film feeding

means comprising rotating sprockets and a reciprocating lever for feeding a developed and an undeveloped film simultaneously through the machine; a pay out reel and a take up reel for holding the undeveloped film; a pay out reel and a take up reel for holding the developed film; means for causing said first named pay out reel to function as a take up reel; means to cause said second mentioned pay out reel to function as a take up reel; and means for operating both of said take up reels whenever functioning as such from the same shaft, substantially as described.

3. In a film printing and projecting apparatus the combination of a film feeding means comprising rotating sprockets and a reciprocating lever for feeding a developed and an undeveloped film simultaneously through the machine; a pay out reel and a take up reel for holding the undeveloped film; a pay out reel and a take up reel for holding the developed film; a casing for enclosing said first named pair of reels and said film feeding means and provided with 90 slots through which said developed film enters and leaves said casing; and means for operating both of said take up reels from the same shaft, substantially as described.

4. In a film printing apparatus the combination of a casing; means located in said casing to exclude light and providing an aperture; additional means located in said casing providing a second aperture registering with said first named aperture; means for opening and closing said second named aperture at will; means for feeding a developed and an undeveloped film in close contact between said apertures; and means located in said casing whereby the operator may view the back of said undeveloped film through said second named aperture, substantially as described.

5. In a film printing apparatus the combination of a casing; means to exclude light located in said casing and providing an aperture; a second means located in said casing for admitting light to said aperture; means located in said casing provided with an aperture registering with said first named aperture; means in said casing for opening and closing said second named aperture at will; means for feeding a developed and an undeveloped film in close contact between said apertures; and means in said casing comprising a tube provided with a colored glass for aiding the operator to view the back of said undeveloped film through said second named aperture in order to ascertain the quality and quantity of the light entering 125 said first named aperture, substantially as described.

6. In a film printing machine the combination of a casing; an aperture tube in said casing; an opaque means in said casing as-

- sociated with said tube and provided with an aperture adapted to register with said first named aperture; means in said casing for opening and closing said second named 5 aperture at will; and a viewing tube in said casing provided with a ruby glass in register with said apertures adapted to aid the operator in viewing said second named aperture during the printing operation, substantially as described.
7. In a printing machine the combination of a casing provided with a pair of light tight slots through which a developed film may enter and leave said casing; a pay out 15 reel and a take up reel located in said casing adapted to carry an undeveloped film; an aperture tube located in said casing; an opaque plate located in said casing having an aperture in register with said tube; 20 means comprising a sprocket and a reciprocating lever located in said casing for simultaneously feeding said developed and said undeveloped films between said apertures; means in said casing for opening and closing said second named aperture at will; a 25 tube located in said casing passing through the axes of said reels for aiding the operator to view the back of said undeveloped film through said second named aperture when the latter is open; and a colored glass located in said tube adapted to prevent actinic rays from entering said second named aperture and fogging said undeveloped film, substantially as described.
7. In a printing machine the combination of a casing provided with a pair of light tight slots through which a developed film may enter and leave said casing; a pay out reel and a take up reel located in said casing adapted to carry an undeveloped film; an aperture tube located in said casing; an opaque plate located in said casing having an aperture in register with said tube; 20 means comprising a sprocket and a reciprocating lever located in said casing for simultaneously feeding said developed and said undeveloped films between said apertures; means in said casing for opening and closing said second named aperture at will; a 25 tube located in said casing passing through the axes of said reels for aiding the operator to view the back of said undeveloped film through said second named aperture when the latter is open; and a colored glass located in said tube adapted to prevent actinic rays from entering said second named aperture and fogging said undeveloped film, substantially as described.
7. In a printing machine the combination of a casing provided with a pair of light tight slots through which a developed film may enter and leave said casing; a pay out reel and a take up reel located in said casing adapted to carry an undeveloped film; an aperture tube located in said casing; an opaque plate located in said casing having an aperture in register with said tube; 20 means comprising a sprocket and a reciprocating lever located in said casing for simultaneously feeding said developed and said undeveloped films between said apertures; means in said casing for opening and closing said second named aperture at will; a 25 tube located in said casing passing through the axes of said reels for aiding the operator to view the back of said undeveloped film through said second named aperture when the latter is open; and a colored glass located in said tube adapted to prevent actinic rays from entering said second named aperture and fogging said undeveloped film, substantially as described.

In testimony whereof we affix our signatures in presence of two witnesses.
